Primary Examiner — Leanne Was-Englehart

(74) Attorney, Agent, or Firm — Lippes Mathias LLP

(57) **CLAIM**

The ornamental design for an inflatable fence as shown and described.

DESCRIPTION

FIG. 1 is a front perspective view of an inflatable fence in accordance with the present design;

FIG. 2 is a front elevational view of the inflatable fence of FIG. 1;

FIG. 3 is a rear elevational view of the inflatable fence of FIG. 1;

FIG. 4 is a right side elevational view of the inflatable fence of FIG. 1;

FIG. 5 is a left side elevational view of the inflatable fence of FIG. 1; and,

FIG. 6 is a top plan view of the inflatable fence of FIG. 1. The broken lines depict portions of the inflatable fence that form no part of the claimed design.
